(57) **CLAIM**

The ornamental design for a knob, as shown and described.

DESCRIPTION

FIG. 1 is a front perspective view of a knob showing my new design;

FIG. 2 is a rear perspective view thereof;

FIG. 3 is a front elevational view thereof;

FIG. 4 is a left side view thereof;

FIG. 5 is rear view thereof;

FIG. 6 is a right side view thereof;

FIG. 7 is a top plan view thereof; and,

FIG. 8 is a bottom view thereof.

The broken lines are included for the purpose of illustrating portions of the knob and form no part of the claimed design.
